UNITED STATES PATENT OFFICE.

ALFRED P. SLOAN, JR., OF BROOKLYN, NEW YORK, ASSIGNOR TO HYATT ROLLER BEARING COMPANY, OF HARRISON, NEW JERSEY, A CORPORATION OF NEW JERSEY.

STEEL-LINED ROLLER-BEARING.

No. 876,499.

Specification of Letters Patent.

Patented Jan. 14, 1908.

Application filed December 13, 1904; Serial No. 236,686. Renewed January 2, 1907. Serial No. 350,430.

To all whom it may concern:

Be it known that I, ALFRED P. SLOAN, Jr., a citizen of the United States, residing at No. 275 Clinton avenue, Brooklyn, county 5 of Kings, and State of New York, have invented certain new and useful Improvements in Steel-Lined Roller-Bearings, fully described and represented in the following specification and the accompanying drawings, forming a part of the same.

The object of this invention is to furnish an improved construction whereby a steel lining can be applied economically to a cast metal casing having integral flanges at opposite ends, for use in a hanger-box. Such 15 cast metal casings have heretofore been made open at one end to facilitate the introduction of a boring tool or cutter for truing out the cylindrical seat which supports the lining; but such a construction necessitates the fastening of a flange to a box, which flange is liable to become loosened.

In the present invention, the flanges are made integral with the casing, and the boring is effected by forming recesses within 25 the casing near its opposite ends of sufficient diameter to clear the boring cutter. The casing is made in halves with bolting lugs to clamp the halves together around 30 a boring bar carrying a suitable cutter, which enters one of the recesses, the casing or bar being then fed longitudinally and the cutter traversed from one of the recesses to the other, thus boring out the seat for the 35 lining.

The lining is prepared for application to the casing by forming it in halves and clamping the halves in a suitable clamping box under a boring tool, which is then fed 40 through the lining to bore its interior. The halves of the lining are furnished each near one end with a hole which fits a stud in the clamping box to hold the lining from rotation during the boring operation, and such 45 holes are located to coincide with oil-holes upon the casing when the lining is fitted therein. The lining extends from one flange to the other within the casing and thus covers the recesses and furnishes a continuous support for the anti-friction rolls.

In the drawing, Figure 1 is a plan of the roller bearing adapted for a hanger-box; Fig. 2 is a cross section of the same on line 2, 2, in Fig. 1, with the anti-friction rolls and a shaft 50 fitted therein; Fig. 3 is a vertical section of

the same with the boring-bar and cutter arranged for truing out the interior seat; Fig. 4 is a plan of the cap for the upper oil-hole; Fig. 5 is a longitudinal section of the same; Fig. 6 is a vertical section of the clamping box used in boring the lining; and Fig. 7 shows the sheet steel blank for half of the lining.

a designates the casing which is formed in halves and provided with the flanges *b* and *b'*, which cover the ends of the anti-friction rolls *r*, which are shown only in Fig. 2 with the roll-guide *r'*. A narrow recess *c* is formed in the casing contiguous to the flange *b*, and a relatively wider recess *d* is 60 formed at a little distance from the flange *b'*, the recess *d* being made of larger diameter and greater width than the diameter and thickness of the cutter *C*, which is shown in Fig. 3 mounted upon a driving mandrel 70 on boring-bar *D*.

To prepare the casing to receive the lining *f*, the cutter is first traversed from the recess *d* to the flange *b'*, forming a short seat *f'* to support one end of the lining and truing off 80 the inner side of the flange *b'*, against which the end of the anti-friction rolls or their guide, rotates. The cutter is then traversed from the recess *d* to the recess *c*, forming the seat *e* and facing off the inner side of the 85 flange *b*. The recess *c* makes a clearance space for the chips which are formed by the cutter in facing the flange *b*; while the recess *d* forms a clearance for the cutter when the 90 casing is bolted together over the same before any of the seats have been bored. In the lower half of Fig. 3, the lining is shown extended the whole length of the casing, the lower edge of the cutter being broken away to clear the same; but in the upper half of 95 Fig. 3, the casing is shown in the right hand half without the lining, and the material indicated by the dotted lines *e'*, which would be removed by the cutter to produce the required seats for the lining and rolls. The 100 halves of the casing being unbolted can then be removed from the cutter *C* and mandrel *D*, and are in readiness to receive the lining. The lining is made of two tapering blanks *F*, as shown in Fig. 7, each forming one half of 105 the lining *f* when rolled to semi-cylindrical shape.

A hole *h* or *h'* is punched in the middle of each blank near one end, and the halves are then fitted together, with their wide and nar- 110

row ends adjacent inside a clamping box A, shown in Fig. 6, which is provided with studs B to fit the holes h and h' and thus hold the lining from turning. A boring tool n is represented diagrammatically in Fig. 6, which, when forced downward in the lining serves to bore the same out in readiness to support the anti-friction rolls. When thus bored, the halves of the lining are fitted into 10 the halves of the casing, as shown in Fig. 1, and in the left hand end of Fig. 3, and secured therein by rivets o .

The holes g and g' in the casing are so located as to coincide with the holes in the two 15 halves of the lining, which are marked h and h' in Fig. 3, and the oil-hole g upon the top of the casing is formed with an upwardly projecting collar p , adjacent to which a hingelug i is formed upon the casing. A cap j is 20 hinged upon the lug i and provided with rearwardly projecting toes k which prevent the cap from being lifted into a vertical position, it is thus compelled, after being lifted, to fall back upon the collar and close the oil-hole. The cap is formed with a flange l which surrounds the collar p when the cap is 25 closed, so as to exclude dust from the oil-hole g , and the flange l is formed at intervals with notches l' which permit the nozzle of an oil 30 can to be inserted through the notches when the cap is partially raised and oil thus furnished to the oil-hole g without raising the cap very far. This is an advantage in the case of hanger-boxes where the hangers are 35 attached to the ceiling, and access to the cap and oil-holes is frequently obstructed. The oil-hole g' in the bottom of the casing permits the worn or waste oil to drain out of the bearing.

40 The blank F for the lining is shown in Fig. 7 tapered toward both ends, and when two such blanks are put together with the wide and narrow ends in contact, they can be rolled to form a complete cylinder with 45 oblique joints at opposite sides of the same. Such oblique joint in the lining f is shown at f^4 in Figs. 3 and 6, and permits the anti-friction rolls to move smoothly over the joint, and thus prevents any jar which would 50 be occasioned if the joint were parallel with the bore and the entire length of the roll thus crosses the joint at once.

In Fig. 2, the division between the two 55 parts of the casing is arranged vertically, by the projection of this view from the plan in Fig. 1, and it will be observed that the joint of the sheet-steel lining in Fig. 2 extends at both sides above the joint between the halves of the casing.

60 Fig. 3 shows that, at the opposite end of the box, the joint of the lining is below the division between the halves of the casing; and the tapering form of the two blanks from which the lining is made thus causes

the linings to project, at opposite ends of 65 the casing, into opposite halves of the same, which assists materially in supporting the joint of the lining, as such joint does not coincide with the division or joint of the casing. The oblique joint of the lining thus 70 performs the double function in easing the rotation of the anti-friction rolls, and in steady- 75 ing the joint of the lining.

It will be observed that in the finished article both the casing as well as the lining 75 is furnished with a finished cylindrical bore, which assists materially in supporting the lining with firmness and holding its finished surface truly in cylindrical shape.

The formation of the recesses c and d in 80 the halves of the casing greatly facilitates the manufacture, by permitting the clamping of the two halves of the casing together outside of the cutter before the seat e is bored.

Having thus set forth the nature of the invention what is claimed herein is:

1. In a hanger box, the combination, with the cast-metal casing a divided longitudinally in halves and having flanges b, b' at opposite ends, and the finished cylindrical seat e' , of the steel lining f divided longitudinally off of the center line, and means for fastening the halves respectively to the seat in the halves of the casing, the interior of 95 the lining having a finished cylindrical bore, substantially as herein set forth.

2. A hanger box having the cast-metal casing with integral flanges at opposite ends and divided as set forth, and formed with 100 the finished cylindrical seat between the said flanges, and the steel lining f formed in two pieces, each made wider at one end than the other, with their wide and narrow ends fitted together within the casing, and the two 105 pieces secured thereto with the sloping joint at the division of the casing, to facilitate the movement of the rolls upon the lining.

3. In a hanger box, the combination, with the divided cast-metal casing a with integral 110 flanges b, b' at opposite ends, and having the finished cylindrical seat e and the oil-holes g and g' extended through the top and bottom near opposite ends as set forth, of the steel lining f formed in halves fastened 115 respectively to the seat in the halves of the casing and having a finished cylindrical bore, and provided with the holes h and h' arranged to coincide with the casing oil-holes g and g' respectively.

In testimony whereof I have hereunto set 120 my hand in the presence of two subscribing witnesses.

ALFRED P. SLOAN, JR.
